UNITED STATES PATENT OFFICE.

CARL T. LARSON, OF MOLINE, ILLINOIS.

MONOLITHIC WALL AND MOLD THEREFOR.

Application filed March 27, 1924. Serial No. 702,422.

To all whom it may concern:

Be it known that I, CARL T. LARSON, a citizen of the United States, residing at Moline, in the county of Rock Island and 5 State of Illinois, have invented certain new and useful Improvements in Monolithic Walls and Molds Therefor; and I do declare the following to be a full, clear, and exact description of the invention, such as 10 will enable others skilled in the art to which it appertains to make and use the same.

My invention relates to the construction of monolithic walls from cement and relates more particularly to walls in which air 15 spaces are formed between the outer and inner sides of the wall, by suitably shaped cores of cardboard or other desired material, which are left in the completed wall.

The principal object of the invention is 20 to provide novel devices for supporting any desired number of the cores one upon the other, in spaced relation with the sides of a mold, into which the cement is poured to form the wall.

25 Another object of the invention is to provide a simple and inexpensive, yet an efficient and very desirable mold, within which the wall is cast.

With the foregoing in view, the invention 30 resides in the novel subject matter herein-after described and claimed, the description being supplemented by the accompanying drawings.

Figure 1 is a vertical transverse sectional view of a wall and mold constructed in accordance with my invention.

Figure 2 is a horizontal sectional view on line 2—2 of Fig. 1.

Figures 3 and 4 are vertical longitudinal 40 sectional views as indicated by lines 3—3 and 4—4 of Fig. 1.

Figures 5 and 5^a are perspective views of the holders and spacers for the cores.

Figure 6 is a perspective view showing 45 three sections of the mold.

In the drawings above briefly described, the numeral 1 designates a mold for a cement wall, and while a mold of one specific construction is shown, it will be obvious 50 that certain features hereinafter described, can be used in connection with any form of mold.

The numerals 2 designate a plurality of hollow cores disposed within the mold 1 in spaced relation with its opposite sides. 55 These cores may be formed of numerous shapes, sizes and materials, but I prefer to construct them of suitable water-proof cardboard, of a length to extend substantially from one end of a wall to the other. To 60 properly position the cores 2 with respect to each other and with respect to the walls of the mold, I provide the novel means described below, attention being now directed more particularly to Fig. 5. 65

The numeral 3 designates an elongated strip of sheet metal having an upwardly bent flange 4 at one edge of each of its ends and a downwardly bent flange 5 at the other edge of each of its ends, the distance between the inner ends of said flanges being sufficient to permit reception of one of the cores 2 between said ends. The intermediate portion of the strip 3 is shown as provided with parallel vertical flanges 6 of less 70 height than the other flanges, said flanges 6 being of such a height or width as to space the superposed cores 2 the proper distances from each other.

In building a wall, a portion of the mold 1 is assembled from the ground to any desired level, a plurality of the strips 3 are placed transversely in the bottom of said mold with their ends abutting the mold walls, one elongated core 2 or possibly a 80 series of shorter cores are placed upon these strips between the endmost upwardly projecting flanges thereof, so that the sides of the core are properly spaced from the walls of the mold, a second series of the strips 3 85 is then placed upon the core or cores previously inserted, a second core or a row of short cores is then placed upon the second series of strips, and so on, until the cores are about even with the top of the mold. 90 Then, green cement is poured into said mold and it will fill the spaces between the mold walls of the core and will run in between the vertically spaced cores, so that when the cement sets, a monolithic wall is provided, which is formed with vertically 95 spaced air passages.

In some instances, it is not desired to have the inner and outer portions 7 and 8 of

the cement wall, connected by webs of cement 9, such as shown in Figs. 1 and 3. To produce a wall of this type, the strips shown in Fig. 5^a may be used, which strips 5 will not vertically space the cores to any appreciable extent. In this figure, the numeral 3^a designates a flat metal strip having upstanding flanges 4^a at the ends of one edge and downwardly extending flanges 10 5^a at the ends of its other edge, the intermediate portion of said strip being free of flanges, such as those above designated by the numeral 6.

The mold 1 preferably comprises a plurality 15 or rectangular sections 10 formed of suitable gauge sheet metal, the upper and lower edges of said sections being bent laterally outward to provide flanges 11 which are in turn bent at their free edges 20 to provide vertical flanges 12. When the mold sections are set one upon another, the flanges 11 contact with each other and the flanges 12 are then adapted to engage the inner sides of suitable vertical studs 13, to 25 which said flanges may be clamped by suitable C-clamps 14. Preferably, the contacting flanges 11 are formed with registering openings 15 through which one end of each clamp may pass, so that said end may jointly 30 contact with two adjacent flanges 12, as seen in Fig. 1.

The studs 13 may be held against spreading by any suitable means. Preferably, however, longitudinally tapered tie-bars 16 35 are passed through openings 17 in said studs and through similar openings 18 in the mold sections and the cores 2. Each of the rods 16 may well have a shoulder 19 at one end to engage the outer side of one 40 of the studs 13, and may be provided with a removable locking plate 20 at its other end to engage the outer side of the other stud. After the wall has set sufficiently to permit the mold to be removed, the locking 45 plates 20 of the several bars 16 are removed and said bars are driven out of place. By then removing the clamps 14, it will be seen that all of the mold sections may be disassembled.

50 Preferably, in addition to the clamps above described, additional C-clamps 21 are used at suitable intervals, to clamp the horizontal flanges 11 in contact with each other.

55 By carrying out my invention, an efficient monolithic wall may be easily and inexpensively produced and obviously, the inner and outer sides of this wall may be finished in any desired manner.

60 As excellent results are obtainable from the details disclosed, they are preferably followed, but within the scope of the invention as claimed, numerous changes may be made.

I claim:

65 1. Means for forming air spaces in a

poured cement wall, comprising a plurality of superimposed cores permanently disposed between vertical mold walls, and a plurality of transverse strips permanently supporting said cores one upon another, all 70 of said strips being spaced widely apart vertically and being of an infinitesimal vertical dimension with respect to the height of any core.

2. Means for forming air spaces in a 75 poured cement wall, comprising a plurality of superimposed cores disposed permanently between vertical mold walls, and a plurality of transverse strips permanently supporting said cores one upon another, said strips abutting said mold walls and having shoulders engaging the outer sides of said cores to hold the latter in properly spaced relation with said mold walls, all of said strips being spaced widely apart vertically 80 and being of an infinitesimal vertical dimension with respect to the height of any core.

3. Means for forming air spaces in a 85 poured cement wall, comprising superimposed cores disposed between vertical mold 90 walls, and transverse strips between said superimposed cores and supporting them one upon another, the ends of said strips having oppositely bent vertical flanges 95 engaging the outer sides of said cores to space the latter from said mold walls with which the ends of said strips contact.

4. A structure as specified in claim 3; 100 said strips having parallel flanges along intermediate portions and extending in the same direction therefrom, said parallel flanges being of less height than the other flanges extending in the same direction.

5. A spacing device of the class described 105 comprising an elongated strip adapted to be interposed between upper and lower cores and to abut spaced mold walls at its ends, said strip having an upwardly bent flange at each end and a downwardly bent flange at each end, said flanges being adapted to 110 engage the cores to hold the latter in properly spaced relation with the mold walls, the intermediate portion of said strip having vertically bent parallel flanges extending in the same direction therefrom, said parallel flanges being of less width than the other flanges extending in the same direction.

6. A mold comprising a plurality of 120 rectangular metal sections having their upper and lower edges bent outwardly to provide horizontal flanges, said flanges of adjacent sections being adapted to be clamped together, the outer edges of said flanges having vertically extended flanges 125 adapted to be clamped against vertical studs, said horizontal flanges having registering openings adjacent said vertical flanges to permit one end of the clamp to jointly engage adjacent vertical flanges.

7. A spacing device of the class described comprising an elongated strip adapted to be interposed between upper and lower cores and to abut spaced mold walls, the ends of said strip having upwardly and downwardly bent portions providing inwardly facing shoulders to engage opposite sides of the

cores, said strip also having a vertically bent portion between said shoulders to space said cores apart vertically. 10

In testimony whereof I have hereunto affixed my signature.

CARL T. LARSON.
